UNITED STATES PATENT OFFICE.

ARTHUR ALFRED BUREAU, OF CHICAGO, ILLINOIS, ASSIGNEE TO WESTERN ELECTRIC COMPANY, INCORPORATED, OF NEW YORK, N. Y., A CORPORATION OF NEW YORK.

METHOD OF AND APPARATUS FOR APPLYING THE LATERAL SURFACES ON CONTAINERS.

Application filed November 17, 1926. Serial No. 143,990.

This invention relates to a method of and apparatus for applying the lateral surfaces on containers, and more particularly to a method of and apparatus for positioning and 5 retaining lags on cable reels.

Heretofore it has been a practice in some instances to lag cable reels by nailing the lags to the heads of the reel which involves a considerable amount of time and labor and 10 after the lags have been nailed on a reel several times the heads become badly damaged by the nails. In some cases reel heads thus damaged become useless, while in other cases considerable expense must be incurred 15 to make them serviceable. Numerous attempts have been made to retain the lags on the reel by means of straps or bands which have proven that it was difficult if not impossible to draw the straps or bands tight 20 enough to retain the lags firmly on the reel when the reel is rolled on the lags during transportation.

An object of the present invention is to provide a convenient and effective method of 25 and apparatus for positioning enclosing elements and retaining them securely on the end members by means of straps or bands, which have obviated the difficulties heretofore encountered.

30 In accordance with one embodiment, the invention contemplates fastening a pair of straps to a cable reel, rotating the reel as the lags are positioned between the reel head and the straps and when the lags have been 35 positioned, the straps are sealed while the lags are deflected inwardly at a central point.

It is believed that a complete understanding of the invention may be had by reference to the following description taken in 40 conjunction with the accompanying drawing illustrating an apparatus embodying the invention and which may be employed in practicing the improved method, and in which—

Fig. 1 is a side elevation of the apparatus 45 corresponding to a view taken on the line 1—1 of Fig. 2;

Fig. 2 is a plan view of the apparatus shown in Fig. 1;

Fig. 3 is an enlarged fragmentary sectional view taken on the lines 3—3 of Fig. 2 illustrating the manner in which the individual lags are deflected, and

Fig. 4 is an enlarged fragmentary sectional view taken on line 4—4 of Fig. 2.

Referring to the drawing in which similar reference characters represent the same parts in the several views, a reel 6 of any suitable character such as is frequently used for transporting lead covered cable is represented as rotatably mounted on a shaft 7 supported by a pair of jacks 8—8. A pair of braces 9—9 are provided to receive the thrust of a positioning and banding apparatus 11, the upper portions of the braces being provided with channel shaped guide members 12—12 which engage the sides of square heads 13—13 of the jacks. 55 60 65

The positioning and banding apparatus is mounted on a pair of standards 14—14, the upper face of each of which is provided with 70 a pair of supports 15—15 which carry an angularly shaped member 16 upon which bearings 17—17 are slidably mounted. A shaft 18 carrying two drums 19—19 is rotatably mounted in the bearings and is provided with a hand wheel 21 to rotate the drums. The drums may be moved toward and away from the reel by means of a pair of screws 22—22 which engage threaded portions 23—23 of the bearings to adjust the 80 apparatus to accommodate various sizes of reels. A pair of spools 24—24 carrying straps or bands 25—25 of any suitable type used for securing the lags of the reel are mounted under the apparatus and the straps 85 are fed therefrom through spring pressed tension members 26—26 between guide members 27—27, and over the drums to the reel.

In order to prevent a longitudinal displacement of the lags, they are each provided with a notch or cutaway portion 28 (Fig. 3) at either end leaving shoulders 29—29 to engage the internal faces of reel heads 31—31 so that the ends of the lags will remain flush with the external faces of the 95 reel heads. The opposite face of each lag is provided with a pair of grooves 33—33 which serve to retain the straps in definite positions and also prevent them from protruding above the surface of the reel. 90 95 100

In practicing the method of this invention, the reel 6 is rolled into position, the shaft 7 is inserted in the reel and the jacks are then raised until the reel is free to turn. A first lag 32 is then nailed on the reel, which may be permanent or only temporary, and the ends of the straps or bands are nailed to the lag in the grooves 33—33. When the 105

first lag has been nailed to the reel and the straps attached thereto, the drum may be rotated by means of a hand wheel 21, and the reel heads may be rotated by hand, the 5 remaining lags being fed into the space between the rotating drum and reel heads. The tension means 26-26 are so adjusted as to retain the bands sufficiently taut to hold the lags firmly against the reel heads until 10 all of the lags have been positioned. A cable 34 is then led from hook 37 under and around the reel and secured to hook 36, and a high tension is produced in the cable by means of a turnbuckle 35 secured in the hook 15 37. This results in a considerable deflection of each of the lags about the entire reel (Fig. 3), and while the lags are thus deflected, the straps 25-25 are drawn snugly about the reel in the grooves 33-33 and the ends of 20 each of the straps are then sealed in accordance with means well known in the art. After the straps are sealed, the cable 34 may be removed which will allow the lags 32 to assume a less deflected position and any slack 25 which may have been present in the straps or bands will be taken up and the lags will be held firmly on the reel heads for all practical purposes. The reel may then be removed from the apparatus and the process 30 repeated on other reels.

It will be understood that the embodiment of the invention herein described and illustrated is merely a convenient and useful form of the invention which is capable of 35 many other modifications without departing from the spirit and scope of the invention.

What is claimed is:

1. A method of applying lags on circular 40 end members, which consists of rotatably mounting the end members, securing one lag thereto, attaching a strap to the secured lag, feeding the remaining lags between the end members and the strap to position the lags as the end members are rotated, deflecting 45 the lags after they are positioned, sealing the strap while the lags are deflected, and decreasing the deflection of the lags to firmly engage the strap against the lags.

2. A method of applying lags on circular 50 end members, which consists of securing one lag to the members, attaching a pair of straps to the secured lag, positioning the remaining lags between the straps and the circular end members, retaining the lags in 55 position by applying a tension to the straps, applying a deflecting force to the lags after they have been positioned, sealing the straps while the lags are deflected, and withdrawing the deflecting force to vary the degree 60 of deflection of the lags.

3. In an apparatus for applying lags on circular end members, means for positioning the lags on the end members, means for retaining the positioned lags until all of the lags have been positioned, and means for 65 deflecting the lags at a central point while the retaining means are sealed.

4. In an apparatus for applying lags on circular end members, means for rotatably mounting the end members, means including 70 a drum for simultaneously positioning the lags on the end members and a retaining band therearound, and means for adjusting the position of the drum to accommodate the apparatus for end members of various sizes. 75

5. In an apparatus for applying lags on circular end members, adjustable means for rotatably mounting end members of different sizes, means including drums for simultaneously positioning lags and a plurality of 80 tensioned retaining bands around the end members, and means for adjusting the drums to correspond with the adjustment of the mounting means for different sizes of end members. 85

6. A method of applying enclosing elements on end members which consists in securing one end of a flexible member to one of the enclosing elements, then feeding enclosing elements between the flexible member 90 and the end members to completely surround the end members, applying pressure to flex the enclosing elements inwardly, interconnecting the ends of the flexible member to secure the enclosing elements upon the 95 end members, and releasing the pressure.

7. A method of applying enclosing elements to spaced end members to form a container, which consists in placing the enclosing elements upon the end members to completely surround the same, applying pressure to deflect the enclosing elements inwardly between the end members, securing a flexible member snugly around the enclosing members, and releasing the pressure to 100 put the flexible member under tension. 105

8. A method of applying notched lags to the circular end members of a cable reel, which consists in placing the lags across the end members to completely surround the 110 same, applying pressure to deflect the lags inwardly between the end members, placing a strap snugly around the lags, securing the ends of the strap together, and releasing the pressure to put the strap under tension. 115

In witness whereof, I hereunto subscribe my name this 6th day of November, A. D. 1926.

ARTHUR ALFRED BUREAU.
